METER SHUNT PREVENTING MEANS

LeRoy Search, Wesleyville, Pa.

Application December 29, 1933, Serial No. 704,394

3 Claims. (Cl. 171—34)

This invention pertains to means preventing by-passing of current around an electric energy recording meter whereby unrecorded electrical energy may be obtained.

Electric power dispensing companies are increasingly confronted with the problem of preventing "current stealing", two of the most common forms of securing unrecorded energy being the use of a U shaped jumper inserted so as to directly contact the meter terminals or relatively minute contacts projected through the insulation of one of the power leads and through the insulation of the corresponding load line.

The various types of watt-hour meters whether of the Thomson type or the mercury flotation type operate in a generally similar manner and comprise a small motor whose instantaneous speed is proportional to the power passing through it, and whose total revolutions in a given time are proportional to the total energy or watt-hours delivered during that time. One side of the line is connected in series with the field coils and the armature is connected across the line, the retarding torque being provided by a disc such as aluminum rotating between a magnetic field of constant strength.

Obviously if the current is shunted around the field coils as previously described the meter will run slow and only a relatively small amount of energy will be recorded.

Although various means to effect retarding of the disc movement are employed the aforementioned means are the most widely used and most difficult to detect and combat.

I have devised a means of rendering the aforementioned methods ineffective for the purpose desired and whereby the fuses controlling the power lines will be blown.

It is the object of my invention therefore to provide a means preventing unauthorized consumption of electrical energy.

Another object of my invention is to render the power lines inoperative when an effort is made to shunt current around the meter.

Another object of my invention is to provide improved means preventing access to the meter terminals.

Other objects of the invention and the invention itself will become increasingly apparent from a consideration of the following description and drawing wherein Fig. 1 is a preferred embodiment of my invention as applied to a conventional two wire system; Fig. 2 is a wiring diagram of the construction illustrated in Fig. 1; Fig. 3 is a side elevational view of the embodiment shown in Fig. 1.

Fig. 4 is an enlarged fragmentary view of terminals which I may employ in connection with the embodiment illustrated in Fig. 1;

Fig. 5 is an enlarged fragmentary sectional view taken along the line 5—5 of Fig. 1;

Fig. 6 is a fragmentary elevational view of a modification of my invention as applied to a three-wire system and Fig. 7 is a wiring diagram of the three-wire system illustrated in Fig. 6.

Referring now to the drawing I have shown at 1 a conventional watt-hour meter which may be either of the Thomson or mercury flotation type and having contacts 2 and 3 extending from the power line terminals, and contacts 4 and 5 extending from the load line terminals. The contact 2 is connected to a power line externally of the building through a terminal 6, line 7, one pole 8 of a two pole switch, fuse 9, and line 10. Contact 3 is connected to the external power line through terminal 11, line 12, the other pole 8a of the switch, fuse 9a, and line 13. Contact 4 connects with the load line 14 through terminal 15 and contact 5 connects with load line 16 through terminal 17.

The terminals and contacts are disposed within a preferably box-shaped structure generally indicated at 18 and formed of bakelite or other suitable insulating material, the box 18 being flush with the rear wall of the meter and secured to a suitable support 19 by any desirable means such as bolts 20 projected through the base of the structure and engaging the support. The box 18 is provided with upstanding sides of a uniform height and is cut away as indicated at 21 to closely engage the portion of the meter base disposed therein.

The base of box 18 has upstanding ribs as indicated at 22 integral therewith and adapted to act as insulating mediums preventing contact of the terminals 6, 11, 15 and 17. Outwardly of terminals 6 and 17 are disposed ribs 23—23 abutting the base of the meter and preventing wires which might be inserted intermediate the meter 40 and box 18 despite their abutting relationship from engaging terminals 6 and 17 or contacts 2 and 5.

The lines 7, 12, 14 and 16 are projected upwardly to engage their respective terminals through perforations provided therefor in the bottom wall of box 18. I contemplate that the aforementioned lines will make a sufficiently tight engagement with box 18 to prevent wires or the like being projected through the box to engage the terminals but as will be hereinafter described should such wires be so projected they will be ineffective to obtain the desired result of shunting current around the meter.

Lines 7 and 16 are connected in series with the field coils of the meter and consequently these are the lines which are inter-connected externally of the meter or at the meter terminals to shunt out the field coils. Inter-connecting any other combination of lines externally of the

meter or at the meter terminals would cause a direct short blowing the fuses or would be ineffective to shunt out the field coils and accomplish the desired result.

5 I provide a relatively thin conducting sheath 25 preferably formed of copper braid which is telescoped over the insulation of line 7 as best illustrated in Fig. 5 the sheath 25 in turn being covered with similar insulating material 26. The 10 sheath being relatively thin does not add materially to the diameter of the conduit and if desired both power lines 7 and 12 may have substantially the same outside diameter.

Although a slight difference in diameter would 15 not lead to the suspicion that either wire was other than the conventional lead in wire. The sheath 25 extends the entire length of line 7 being projected through the fuse box at one end and the box 18 at the other end although it does 20 not contact line 7 at any point. Internally of box 18, sheath 25 is extended beyond the outer insulating sleeve as illustrated in Figs. 1 and 5 and is gripped by a resilient collar 27 having an 25 upwardly extending arm 28 which engages terminal 11. The collar 27 may have sufficient inherent resilience to be sprung around sheath 25 or may be clamped therearound in any suitable manner and is of sufficiently large diameter to prevent any wire or the like which might be projected through the perforation provided for conduit 7 from contacting terminal 6.

The conduit 10 is preferably of a construction similar to conduit 7 and the conduits 7 and 10 are connected internally of the switch box with a 35 conducting line 30. Lines 10 and 13 are projected through the foundation or walls of the building to connect with the outside power lines. It is understood that the conducting sheath encircling the power line of conduit 10 need only be 40 carried outside the building.

The box 18 is provided with a cover 31 of bakelite or the like, the cover being pivotally fixed to box 18 as indicated at 32 and after installation the cover is sealed to the box by seals indicated 45 at 33 and 34 projected through aligned perforations in lugs provided on the box and cover. In a similar manner a cover (not shown) is sealed to the fuse box by seals 35 and 36.

50 Although I have shown a particular type of fuse box I contemplate that a type of box may be employed whereby the fuses may be replaced without unsealing the box.

The operation of the device is as follows: if 55 employing a U type jumper one leg of which might possibly contact terminal 17, the other leg would contact collar 27 thereby effecting a short across lines 12 and 16 and blowing the fuse. The same result would occur if contacts were attempted to be projected through the insulation of 60 lines 16 and 7 since the contact at line 7 would contact the sheath 25 rather than the power line and the fuse would be blown. If lines 10 and 13 were tapped the only effect would be to put one 65 side of the line in series with the top contacts without a return line or if the top contact engaging conduit 10 were projected through the sheath to engage the power line a short circuit directly 70 across the lines 10 and 13 would occur blowing fuse 9a.

75 Although I have shown conduit 10 as being of a construction similar to conduit 7 it is understood that a conventional connection similar to line 13 might be utilized and the connection 30

dispensed with if preventive means at this point is not felt necessary.

In the ordinary hook-up of a meter and fuse box the length of conduit needed such as 7 would be relatively small and in combination with box 18 the above described means provides an effective and inexpensive means of preventing "current stealing".

Referring now to Fig. 6 I have shown an arrangement generally similar to that hereinbefore 10 described as applied to a three wire system.

In this construction a box 50 is provided with terminals 51, 52, and 53 for the power leads, and terminals 54, 55 and 56 for the load leads. Power conduits 57 and 58 similar to conduit 7 are provided, the sheath portions thereof being connected to terminal 52 of the neutral line 59. In this construction one of the meter field coils is in series with power conduit 57 and its corresponding load line and the other field coil is in series 20 with power conduit 58 and its corresponding load line and if an attempt is made to shunt out these coils or either of them a short circuit is effected 25 across the lines resulting in the fuses being blown. The wiring diagram for the three-wire system is illustrated in Fig. 7.

Although I have shown and described modifications of my invention I contemplate that numerous and extensive departures may be made 30 therefrom without departing from the spirit of my invention and the scope of the appended claims.

Having thus described my invention what I claim is:—

1. The combination with a first and second lead-in wire, circuit breaking means associated therewith, an electrical energy recording meter including field coils, a first load line in series with the meter field coils and first lead-in wire, and a second load line in series with the second lead-in wire, of a relatively thin protective conducting sheath encasing the first lead-in wire, insulated therefrom, and connected to the second lead-in wire whereby a shunt inter-connecting the encasing sheath and first load line 45 around the meter coils will interconnect the first and second lead-in wires to cause the circuit breaking means to break the circuit.

2. The combination with a source of current, 50 a meter for recording energy taken from the current source, lead-in wires connecting the current source and meter, circuit breaking means associated with the lead-in wires, and load wires extending from the meter, of a flexible sheath of 55 conducting material encasing one of the lead-in wires and connected to another lead-in wire whereby an attempt to shunt the meter coils by inter-connecting a lead-in wire and load wire in series therewith will inter-connect the lead-in wires to cause the circuit breaking means to break 60 the circuit.

3. The combination with lead-in wires, circuit 65 breaking means, a source of current, and an electrical energy recording meter, of a relatively thin flexible sheath of conducting material extending from the circuit breaking means to the meter encasing one of the lead-in wires, insulated therefrom and connected to another lead-in wire whereby a connection formed with the encasing sheath and a conductor in series with the encased lead-in wire will interconnect the lead-in wires to cause the circuit breaking means to break the circuit.
